UNITED STATES PATENT OFFICE.

HENRY C. SCHLUETER, OF CLEVELAND, OHIO, ASSIGNOR TO WILLIAM ELSEY, OF DETROIT, MICHIGAN.

ROTARY BRUSH.

Application filed August 21, 1926. Serial No. 130,670.

This invention relates to rotary brushes and, especially to that class of brushes in which the bristles or wires are secured to a ring and the ring in turn is secured to a plate which is adapted to fit upon or be fastened to a shaft.

It is the general object of the invention to provide a simple and improved means for mounting the brush proper upon a single plate. A further object of the invention is to provide an inexpensive construction whereby the brush proper may be secured or applied to said plate and one which will enable the brush to be secured to said plate in a quick and convenient manner.

I accomplish the foregoing objects in and through the construction and arrangement of parts shown in the drawing, wherein Fig. 1 represents a side elevation of a brush and plate constructed and assembled in accordance with my invention; and Fig. 2 a detail in section corresponding to the line 2-2 of Fig. 1.

The brush assembly shown herein comprises as a whole a central plate 1 which carries the brush proper consisting of an annular ring having wires or bristles affixed thereto. The plate is provided with an axial opening 2 therethrough by means of which it and the parts associated therewith may be applied and secured to a spindle or shaft. At a suitable distance within and from its periphery, the plate is provided with an annular rib 3 struck therefrom, the said rib providing, on the opposite face of the plate, a concave seat 4 for the reception of the adjacent side and a part of the inner periphery of the brush. The brush comprises an inner ring 5 which is usually formed by twisting several wires together, through which wires the bristles or wires 6 are inserted and then folded over so that the ends of the wires or bristles extend outwardly or radially, presenting their free or operating ends to the work to which the brush may be applied.

Struck from the body of the plate 1, adjacent to and radially inwardly with respect to the rib 3, are tongues 7. The tongues will be struck from the plate 1 so as to extend

substantially at right angles therefrom, as indicated by dot-and-dash lines at 7^a on Fig. 2. This will enable the ring 5 to be slipped over the tongues, until the inner periphery of the brush finds the seat 4, after which the tongues will be bent up into the shape shown in full lines in Fig. 2, so as to complement the seat 4 and provide extensions 7^b substantially parallel with the outer portion of the plate. The brush ring 60 will then be secured against the lateral concave part of the seat 4 and will be held in operative relation thereto and to the annular abutment formed by the inner end of the concavity by the tongues 7.

The construction described hereinbefore enables the ordinary type of brush, comprising the bristles 6 and the wire-ring 5, to be quickly and conveniently applied to and clamped upon the plate 1. In the event that it is desired to replace the brush parts 5 and 6, all that is necessary is to spring the tongues 7 substantially to the position shown at 7^a, whereupon the old brush parts may be removed and new ones substituted.

Having thus described my invention, what I claim is:—

1. A rotary brush comprising a plate having an annular rib extending from one side thereof and located within and spaced from the outer edge thereof, tongues struck from said plate and extending in the opposite direction from said rib, and a brush member comprising a ring and bristles thereon secured by said tongues within the concave seat provided within the said rib.

2. A rotary brush comprising a plate having an annular seat formed within and spaced from the periphery thereof, a brush member comprising a ring having bristles thereon and arranged on said seat, and tongues struck from the plate and bent to engage the brush member, within the said seat, and securing the said member to the said seat.

3. A rotary brush comprising a plate having, within and spaced from the periphery thereof, a seat, a brush member comprising a ring and bristles thereon, and tongues struck from the said plate, within the said

seat, and bent into engagement with the said member, thereby to secure the same to said seat.

4. A rotary brush comprising a plate having an annular rib pressed therefrom, within and spaced from the outer edge thereof, tongues struck from said plate, within the said seat, and extending in the opposite direction from said rib, and a brush member

comprising a ring having bristles thereon and having one side and part of its inner edge supported in the concave seat formed by said rib and secured within said rib and having its opposite side and inner edge supported by the said tongues. 10

In testimony whereof, I hereunto affix my signature. 15

HENRY C. SCHLUETER.
